Patented Dec. 2, 1919.

UNITED STATES PATENT OFFICE.

ALBERT R. TALLMAN, OF NASHVILLE, TENNESSEE.

WATCH AND FOB APPLIANCE.

1,328,383.

Specification of Letters Patent.

Patented Dec. 2, 1919.

Application filed November 26, 1917. Serial No. 204,029.

To all whom it may concern:

Be it known that I, ALBERT R. TALLMAN, a citizen of the United States, residing at Nashville, in the county of Davidson and 5 State of Tennessee, have invented certain new and useful Improvements in Watch and Fob Appliances, of which the following is a specification.

My invention relates to improvements in 10 watch and fob appliances, that is to say an article or device providing a fob and watch attaching means, the leading object being the provision of a cheap, ornamental and efficient device providing a fob and means 15 for attaching the watch, the entire article engaging the pocket and preventing improper detachment of the appliance with the fob and watch.

Another object of my invention is the 20 provision of a device forming a fob and watch attachment which will properly dispose and retain the fob and watch but which will allow easy removal of the article to ascertain the time, and which can be manufactured at such a trifling cost as to produce an 25 article which can be given away or distributed as an advertisement and prove highly desirable for this purpose.

Another object of my invention is the 30 provision of a watch and fob appliance which will be of small size to occupy little space, which can be easily applied and removed from the pocket in a proper manner but which cannot be detached improperly or 35 stolen, and which generally in every particular will prove desirable, efficient and practical.

With these objects in view my invention 40 consists of a watch and fob appliance embodying novel details of construction and arrangement of parts for service, substantially as shown, described and claimed herein.

Figure 1 is a front elevation of one form 45 of my watch and fob appliance.

Fig. 2 is a similar view of a slightly modified construction of the article.

Figs. 3 and 4 are front elevations of other forms of my improvement.

Fig. 5 shows a sectional view of a pocket 50 with my appliance adapted thereto, this form being shown in side elevation and also being of slightly modified construction, and

Fig. 6 is a perspective view of the form 55 of my appliance shown in Fig. 5.

My aim is to produce an article of the simplest and cheapest possible construction

capable of easy and rapid manufacture and consists of a strip or blank of metal of the proper thickness comprising the front plate A, and the inner or rear bent plate B, which 60 forms a clamp for engaging the outer wall C, of the pocket D.

In the form of my invention shown in Fig. 1 the front plate is formed with a disk E, upon which may be placed a monogram or 65 ornamentation E', while in the form shown in Fig. 2 the same construction is used with the addition of the slotted plate F, to receive a ribbon, while in the forms shown in Figs. 3 and 4 the slotted or open frame G is 70 provided which may receive upon the clamping portion the chain H, to which is attached the watch H', or upon the ear J, may be attached the chain K, which suspends the fob K', the open frame in these forms allowing 75 the use either of a ribbon fob or a chain suspended fob, according to the desire of the user.

In Figs. 5 and 6 another form of my invention is shown which consists of the front 80 plate L, and the clamping or bent plate L', which has struck therefrom the lip M, which provides means for attaching the chain N of the watch N', while the front plate is formed with a slotted portion O to receive the fob 85 ribbon O', while teeth O², are provided to retain the ribbon in place. The lower end of the bent member L' is bent so as to form a concave surface L², which is adapted to be engaged by the finger, when the watch is in 90 the pocket and to guide the finger, when the same is moved transversely while in contact with the concave surface so that the finger will be guided under the chain N, which is secured to the finger M, said finger having 95 its end disposed beyond the end of the lower bent end of the member L'.

From the foregoing description taken in connection with the drawings it will be understood that I provide a device which will 100 properly attach the watch and fob and retain them securely in the pocket; which is of ornamental and attractive appearance; and also by reason of its simplicity and cheapness will prove a desirable article of jewelry 105 as well as an excellent advertisement medium.

I claim:

A watch and fob appliance formed from a single piece of spring sheet metal bent upon 110 itself so as to form outer and inner clamping members for engaging the edge of a

5 pocket, the inner member having its free end normally in engagement with the inner face of the outer member, at a point spaced from said end, said inner member being formed
5 with a compound curve so as to engage at said spaced point from its end, said inner member being provided with an outstanding lug substantially centrally thereof to
10 which a watch chain may be secured so that the link or securing means of said watch chain will not interfere with the forcing of

the edge of a pocket between the clamping members, the lower convolution of the inner member extending outwardly so that the edge of the pocket will easily enter between 15 the outer and inner clamping members.

In testimony whereof I affix my signature in the presence of two witnesses.

ALBERT R. TALLMAN.

Witnesses:

SONOMA MASLIN,
ELLA DONELSON.
